UNITED STATES PATENT OFFICE.

LANSING ONDERDONK, OF BOSTON, MASSACHUSETTS, ASSIGNOR TO THE UNION SPECIAL SEWING MACHINE COMPANY, OF CHICAGO, ILLINOIS.

TAKE-UP MECHANISM FOR SEWING-MACHINES.

SPECIFICATION forming part of Letters Patent No. 591,546, dated October 12, 1897.

Application filed January 23, 1896. Renewed August 23, 1897. Serial No. 649,243. (No model.)

To all whom it may concern:

Be it known that I, LANSING ONDERDONK, a citizen of the United States, residing at Boston, in the county of Suffolk, State of Massachusetts, have invented certain new and useful Improvements in Sewing-Machines, (Case F,) of which the following is a description, reference being had to the accompanying drawings and to the letters of reference marked thereon.

My invention relates to an improvement in sewing-machines, and especially to a device for taking up the slack in the under or looper thread in the rearward movement of the looper.

The object is to provide a simple and effective take-up device which is capable of being operated by a moving part of the machine and may be applied outside of the casing or bed-plate, if desired, thereby enabling me on a cylinder-machine to dispense with the enlarged portion at the rear end generally provided for the reception of the take-up cam and nipper-springs.

The take-up mechanism, which *per se* forms the subject-matter of the present case, is described, shown, and claimed in its relation to certain peculiar features of a sewing-machine in a companion application, Case E, filed January 22, 1896, Serial No. 576,593. In the present application, however, it is claimed broadly in its application to any sewing-machine.

The invention includes the matters herein-after described and referred to in the appended claims.

The invention is illustrated in the accompanying drawings, in which—

Figure 1 is a side elevation of so much of a sewing-machine as is necessary to a complete understanding of my invention, showing the take-up mechanism applied thereto. Figs. 2 and 3 are respectively detail views of the cam and reciprocating thread-guiding member.

In the drawings, A represents the base or standard of a sewing-machine; B, the goose-neck; C, the bed-plate or casing, herein shown as of cylindrical shape.

D represents the main shaft operatively connected at its outer end with the looper mechanism and which comprises a rod *a* eccentrically connected to the main shaft, a

looper-carrier *b* on the shaft *c*, which is mounted to slide and rock in bearings in the machine-frame, and *d* is the looper. The feed-dog is herein shown at *e*, and in the particular machine herein illustrated both the looper and feed-dog reciprocate longitudinally of the bed-plate or casing. As far as the present invention is concerned, however, this is an immaterial feature, as the take-up mechanism 55 will work equally well whether the feed be around the arm or up the arm.

E represents the needle arm or lever which operates the needle-bar carrying the needle *f*, the needle-lever being operated from the 60 main shaft in the usual way.

F is the presser-bar, and *g* the presser-foot. As herein shown, the needle arm or lever is provided with a downwardly-projecting extension *G*, through which motion is transmitted to the take-up mechanism. This downwardly-projecting portion may be either integral with or formed separately and then attached to the needle-lever. It carries at its lower end a forked piece *h*, each branch of 70 the fork being provided with an eye *i*, forming guides for the looper-thread. Projecting into the plane of these guiding-eyes and adapted to be engaged by the thread as the forked piece *h* reciprocates back and forth 75 under the action of the needle-lever is a cam-piece *k*, adjustably secured to the machine-frame by slots and screws *l m*. An eye *n*, attached to the machine-frame, and the opening *o* through the casing serve also as guides 80 for the looper-thread, which is laid therethrough and through a suitable guide or eye *p*, secured within the casing, to the looper. While the looper is moving forward and the slack is being taken up by the movement of 85 the piece *h*, which draws the thread over the piece *h*, it is necessary to hold the thread at some point between the take-up and tension to prevent pulling off more thread from the spool, and for this purpose I provide two plates or 90 nipper-springs *q r*, only one of which, *r*, is herein shown as of spring metal, the plate *q* being attached to the machine-frame. The plate *r* is adjustably secured to the plate *q* by slots and screws *s t*, and has a raised portion *u*, upon which is adapted to bear a projection, herein shown as a screw *v* on the nee-

95
100

dle-lever extension, so that as said extension moves forward the needle moves down and the looper backward, whereby the slack on the looper-thread is taken up, and the spring 5 *r* will be compressed against the plate *q*, nipping the thread firmly and preventing any from being pulled off the spool.

Various minor modifications and changes in the construction of this apparatus may be 10 made without departing from the spirit of my invention.

Having thus described my invention, what I claim as new, and desire to secure by Letters Patent, is—

- 15 1. A sewing-machine comprising suitable stitch-forming mechanism including a needle-operating lever having a rigid downward extension thereupon, a forked piece secured to said downward extension, each side of the
- 20 2. fork being provided with a thread-guiding eye, a stationary cam projecting into the plane between the two guiding-eyes, and a thread-clamping device secured to the machine-frame and means carried by the needle-lever and operatively engaging the thread-clamping device to cause the same to grip and release the thread; substantially as described.
- 25 2. In a sewing-machine the combination with the needle the lever operating the same and having a downward extension, the looper and the main driving-shaft, of a positively-actuated take-up for the lower thread consisting of a forked piece provided with a guiding-eye on each part of the fork secured on
- 30 35 said downward extension, a stationary cam projecting into the path of the thread and be-

tween the guiding-eyes, a lug or projection on said lever, and a clamping device for the thread secured to the machine-frame and having a spring member adapted to be operated 40 by the projection or lug on the lever to alternately grip and release the lower thread; substantially as described.

3. A sewing-machine comprising a bed-plate, feeding and looper mechanisms 45 arranged therein, a needle-operating lever having a downward extension and a take-up mechanism comprising a cam, a forked piece attached to said downward extension and reciprocating back and forth in the movement 50 thereof, and means for alternately catching and releasing the thread, substantially as described.

4. A sewing-machine comprising a bed-plate, feeding and looper mechanisms 55 arranged therein, a needle-operating lever having a downward extension, and a take-up mechanism comprising a cam, a forked piece attached to said downward extension and reciprocating back and forth in the movement 60 thereof, a clamping device attached to the machine-frame, and a projection carried on said needle-lever extension adapted in its reciprocation to cause said clamping device alternately to catch and release the thread, substantially as described.

In testimony whereof I affix my signature in presence of two witnesses.

LANSING ONDERDONK.
